CONICAL PLUG REFINER

Cyrus E. Roberson, Hoosick Falls, N. Y., assignor
to The Noble & Wood Machine Company,
Hoosick Falls, N. Y., a corporation of New York

Application February 15, 1949, Serial No. 76,471

9 Claims. (Cl. 92—27)

1

This invention relates to conical plug refining machinery for paper stock and more particularly to improvements in such machinery for controlling both quantity and quality of the paper stock refined. In one aspect this invention relates to improved mechanism in such refiners for maintaining uniform treating conditions despite conditions of substantial wear. In another aspect this invention relates to improved conical plug refining machinery for high degree refining of paper stock.

In general, conventional paper stock refiners of the conical plug type, including the well-known Jordan refiner and its variations, employ a fixed shell in the shape of a hollow truncated cone, and a plug in the shape of a truncated cone fitting into the shell and mounted on a shaft for rotation. The internal surface of the shell and the outer surface of the plug are provided with cutter bars or grooves, and the plug is placed within the shell to give the cutter bars a predetermined cutting clearance before starting. The stock is admitted at the small or apex end and is forced into the space between the cutter bars, whereupon it is cut, fibrillated, and otherwise treated by the action of the bars, and, through pressure of flow and centrifugal force, gradually works toward the larger outlet end.

One of the more important disadvantages in the conventional Jordan-type construction is seen in the limited range of stock quality it is capable of refining without the necessity of major changes in construction. In other words, a Jordan refiner must be initially designed for a given use. If it is desired to obtain highly refined stock the cutter bars must be spaced close together and the clearance between the cutter bars of the shell and the plug must be reduced to a minimum. On the other hand, if it is desirable to treat the stock much less for the production of coarser papers, it is necessary to construct the Jordan with larger bars and wider and deeper grooves. Nowhere in the paper industry has a Jordan refiner been seen which has been capable of producing stock possessing widely divergent characteristics of refinement without the necessity of costly rearrangement of parts prior to changing such characteristics. Of course, a certain degree of variation can be obtained by varying the inlet pressure, the cutter bar clearances, restricting the outlet flow, and varying the rotor speed. However, none of these are conducive to efficient operation and have the disadvantages of requiring complicated control mechanisms. Restricting the outlet flow in par-

2

ticular has the additional disadvantage of causing an oscillatory surge in the flow rendering the degree of refinement uneven.

A further disadvantage in conventional Jordan construction is the inability of such refiners to provide uniform refining conditions over periods of extended use and wear. In general as the cutter bars wear, the plug is advanced into the shell in order to maintain the proper cutting clearance, and in so doing, the wall at the large end of the plug separates from the large shell head, leaving a cavity in the large end of the refiner. This cavity provides a dead space where the paper stock can stagnate during the refining process, and thereby creates a new condition in the refining process which was not present in the earlier operations. Depending on the size of the refiner, this cavity sometimes reaches a width of from six to twelve inches.

20 A further limitation in conventional Jordan-type refiners relates to the degree of refinement that may be obtained by them. Hitherto, Jordan refiners have been incapable of refining paper stock or other fibrous materials down to micron size for the manufacture of glassine, plastics, plasticizers, greaseproof coatings for paper, or the like. The conventional method of achieving such refinement has been to grind the stock between stones, a lengthy and expensive process.

It is an object of my invention to provide a conical plug type refiner capable of varying the quantity and quality of paper stock refined by means of simple adjustments and without the necessity of costly and inconvenient repositioning of members, variations in the inlet and outlet pressures of the stock, variations in the rotational velocity of the plug, or recirculation of stock through the same refiner or additional refiners. Another object of my invention is to provide a conical plug type refiner capable of maintaining substantially uniform refining conditions despite conditions of wear.

45 It is an additional object of my invention to provide a conical plug type refiner for reducing paper stock or other fibrous materials to micron size suitable for use in the manufacture of glassine, plastics, plasticizers, greaseproof coverings for paper, or the like.

In order to accomplish these objects, I employ a rotor plug and stator shell of a Jordan-type refiner. It is not essential to the general application of my invention to use any particular form of conical plug refiner. My improvements are equally applicable to various sizes of shells, plugs and the cutter bars and grooves used with them.

However, in the adaptation of my invention for the production of micronized stock, I preferably employ an all metallic lining having lands and grooves instead of cutter bars and spacers.

It is a feature of my invention that the large end of the plug is tapered toward the shaft, that the inner surface of the large shell head is reciprocally counter tapered, and that the two are spaced apart to form a shallow chamber. This chamber is somewhat similar to the 10 cavity normally occurring in conventional Jordans after the plug has been advanced into the shell due to wear. However, it has slanting walls, and furthermore, the outlet opening for the stock instead of being at the outer periphery 15 is located adjacent to and concentric with the shaft at the inner periphery of the said chamber.

Thus it is impossible for the stock to stagnate in the chamber because the flow of stock is 20 from the outer to the inner periphery of the chamber. While passing through the chamber a swirling motion is imparted to the paper stock by the cutter bars and by the friction of the plug end after the stock leaves the cutter bars. This swirling action, through centrifugal force, sets up a minor separating action, subjects the stock 25 to high pressure, and retards the flow of stock to the outlet.

It is a further feature of my invention that the above mentioned swirling action is interrupted by a turbulence plug located in the large shell head in the wall of the said chamber. The turbulence plug may be projected either directly 30 into the path of the swirling stock to disrupt the said swirling action, or it may achieve the same effect by being withdrawn from the wall of the said chamber leaving a cavity for the purpose of creating turbulence. If the turbulence plug is placed flush with the large shell head wall of the said chamber, no disruption of the swirling action will take place, the stock will be subjected to the maximum centrifugal force, will emit slowly from the stock outlet, and will be 35 highly refined. On the other hand if the turbulence plug is adjusted to disrupt the swirling action, the centrifugal force acting upon the stock will be less, the rate of flow will be greater, and the stock will be less refined.

It is a further feature of my invention that the large shell head is movable with relation to the forward part of the shell and may be connected to the plug shaft bearing supports so that, as the plug is advanced into the shell for the purpose of compensating for cutter bar wear, the large shell head will be kept at a fixed distance from the rear wall of the plug. Thus the chamber between the end of the plug and the large shell head is kept uniform, and despite conditions of wear, substantially uniform refining conditions can be maintained throughout long periods of use.

It is an additional feature of my invention that the connection between the large shell head and the plug shaft bearings is adjustable so that the clearance between the large shell head and the rear wall of the plug may be varied as desired, and the treating conditions with respect to the said chamber between the plug and large shell head may be varied independently of the position of the plug.

Further objects and features of my invention will best be understood and appreciated from a detailed description of a preferred embodiment thereof, selected for the purposes of illustration 75

and shown in the accompanying drawings in which:

Fig. 1 is a view in side elevation of the refiner of my invention.

Fig. 14 is a partially sectioned view in side elevation of the toggle links between the large shell head and the bearing casing.

In its general organization the preferred embodiment of my invention herein shown comprises a heavy cast iron base 10 upon which is mounted a front bearing unit 11, a refiner unit 12 and a rear bearing unit 14. Passing centrally through these units is a shaft 15 which is driven by a conventional source of power not shown. For the purpose of clarity, the refiner unit 12 will be described first and the bearing units later when their function with respect to the operation of the mechanism as a whole becomes more evident.

The refiner unit

The refiner unit includes in its central and rear sections, a conical cast iron or bronze shell 16 essentially of the conventional Jordan refiner type, with the shaft 15 passing axially through it. The shell 16 is preferably made from a single casting, and is supported on the base 10 by suitable braces 17. The inner surface of the said shell 16 is machined to form a conical matrix and is furthermore provided with cutter bars 20 in the conventional manner with wooden spacers not shown. Fitting into this matrix and supported axially for rotation on the shaft 15 is a conical cast iron or bronze plug 21 of complementary shape to the shell 16 and likewise provided with similar cutter bars 22. The edges of the respective cutter bars lie in parallel relationship, and thus, when the plug 21 is advanced axially into the matrix of the shell 16 to a fixed position of clearance between the respective cutter bars, the plug 21 may be rotated to bring about the desired cutting action.

Paper stock is admitted through an inlet opening 24 into a chamber 25 surrounding the shaft 15 in the rear end of the shell. A rear head 26 comprising an upper and a lower casting is bolted to the rear end of the shell 16 by suitable bolts 27.

and constitutes the rear wall of the chamber 25. Packing 28 retained by a packing ring 30 secured to the rear head 26, provides a watertight seal around the shaft 15.

Once the paper stock has entered the chamber 25, it is drawn forward by action of screw blades 31 on the shaft 15 just forward of the chamber 25 but to the rear of the conical plug 21. Paper stock, however, will advance between the shell and the plug without screw blades 31, and therefore, they are optional. Thereafter, the paper stock is caught between the cutter bars 20 and 22 and subjected to their refining action. However, the cutter bars 22 of the rotating plug 21 also impart a circulatory motion to the paper stock which results in a centrifugal force, and in turn tends to aid the progression of the stock towards the large end of the shell 16, by virtue of the expanding slope of the conical shell 16.

Having passed forward of the stationary cutter bars 20 of the shell 16, the paper stock is continued in its circulatory motion within a narrow chamber 33 by action of the forward ends of the rotating cutter bars 22.

The large end of the conical plug 21 is provided with a shallow conical disk 34 suitably secured thereto by machine screws, concentric with the shaft 15 and carried with the said plug in rotation. As the stock proceeds forward from the chamber 33, it passes between the said shallow conical disk 34 and a large shell head 35 which is provided with a rear wall having an inverse taper parallel to that of the said disk 34. The large shell head 35 is held in place by front shell head pieces 40 comprising an upper and a lower casting suitably bolted together and likewise bolted to the forward end of the shell 16 by tie bolts 41. The large shell head 35 is preferably made of cast iron or bronze, and is prevented from following the shaft 15 in rotation by forwardly extending braces 42 (see Figs. 3 and 6) which bear against fixed members but allow the large shell head 35 to move axially with respect to the shell 16 as will be further explained below. The large shell head 35 is likewise provided with a labyrinth seal indicated by the notches 43 for the purpose of preventing stock from leaking out between the large shell head 35 and front shell head pieces 40.

It is to be noted that the opposed walls of the conical disk 34 of the plug 21, and the large shell head 35 are parallel in the preferred embodiment herein shown, but such is not absolutely necessary as these walls may be given a slight varying taper without hindering the operation of the machine.

Paper stock passing forward from the chamber 33 enters a chamber 44 formed by the opposed walls of the shallow conical disk 34 and the large shell head 35. The stock moves through the chamber 44 toward the shaft 15 and eventually passes through an opening 45 in the large shell head adjacent to the shaft, thereafter the stock passes outward through the duct 46 and is used in the conventional manner in paper making process. It will be evident that while the paper stock is in the chambers 33 and 44, it will be subjected to an extreme swirling motion because the said chambers are not provided with cutter bars along their stationary shell surfaces. This swirling motion subjects the stock to an extreme centrifugal counterforce which increases the stock pressure towards the outer end of the chamber 44, retarding the flow towards the opening 45 and promoting refining through surface friction or

hydraulic sheer between the walls of the chamber 44. In order to reduce the said swirling motion of the stock, disruption means such as a turbulence plug or member 47 is provided in the large shell head 35. This plug may be either advanced into the chamber 44 or else it may be withdrawn for the purpose of creating a cavity in the surface of the large shell head 35 which will have the effect of disrupting the centrifugal counterforce by creating turbulence, and thereby increase the rate of throughput of stock.

The retarding plug 47 is shown in detail in Fig. 8 and may preferably be cylindrical in shape with its rear surface machined to the taper angle of the rear wall of the large shell head 35. It is provided with a Monel metal sleeve 48 separating its peripheral surfaces from contact with the large shell head 35 and allowing a free movement of the plug 47 in and out. Connected to the sleeve 48 by a machine screw 50 is a cylindrical bushing 51, an end view of which is shown in Fig. 10. The bushing 51 is provided with an axial groove 52 into which fits a sliding key 53, which in turn is lodged in a groove 54 of a shank extension 55 of the turbulence plug 47 for the purpose of preventing the said turbulence plug 47 from rotating, but to allow it to slide axially. The turbulence plug 47 also has a further extension 57 threaded to receive an adjusting nut 60. The adjusting nut 60 is provided with a laterally extending flange 61 which fits into an appropriately machined recess in the forward end of the bushing 51. A flange plate 62 shown in Figs. 3, 8 and 9 serves to connect the turbulence plug assembly to the large shell head 35 and is secured laterally to the said large shell head by bolts 63 (see Fig. 3) overlaps the said flange 61 of the adjusting nut 60, and furthermore holds the bushing 51 in rigid alignment by appropriate machine screws 64. For the purpose of indicating the exact position of the turbulence plug 47 with respect to the chamber 44, a calibrated indicator 58 is provided as a further extension of the turbulence plug 47. Thus it will be noted that the turbulence plug 47 slides axially within the bushing 51 by adjustment of the nut 60 but is prevented from rotation by means of the sliding key 53. Furthermore, it can be accurately positioned with reference to the calibrated indicator 58.

For the purpose of sealing the forward entrance of the shaft 15 in the large shell head 35, a packing box 65 is provided in the said large shell head. Packing 66 is inserted into the said packing box 65 and held in place by a packing ring 67.

Referring now to the front bearing unit 11 it consists in a conventional bearing case 70 mounting, internally, thrust bearing rollers 96 bearing upon both sides of a double conical sleeve 98 secured to the shaft. The bearing case 70 is provided with laterally extending shoes 100 mounting the bearing for axial sliding movement in guides 71.

The shaft 15 is positioned axially by a thrust screw 102 cooperating with a thrust nut 103 mounted in a forward extension 104 of the bearing case 70. As shown in Fig. 6, with the shaft 15 near its most forward position, the thrust screw 102 enters a recess 105 in the forward end of the shaft 15, merely sliding therein when the shaft rotates. The forward end of the thrust screw 102 is held against axial movement by a conventional double thrust bearing 106, and is rotated by operation of a gear 108 secured to the thrust screw and a cooperating worm gear 110

mounted in the forward end of the bearing unit frame.

Thus it will be evident that the plug 21 and front bearing unit 11 will be moved axially by operation of the thrust screw 102 to compensate for cutter bar wear or to change the cutter bar clearance, and that the large shell head 35 must be correspondingly moved in order to maintain uniform treating conditions in the chamber 44. It may, however, be otherwise desirable to vary the treating conditions in the chamber 44 by varying the space between the disk 34 and the large shell head 35. Therefore, the large shell head 35 is connected to the bearing case 70 by adjustable toggle links (see Fig. 14) on each side of the large shell head 35. The toggle links connect to transfer pieces 84 on the rear wall of the large shell head 35 and each consists in a sleeve 80 having hexagonal heads 81 and being threaded internally to receive connecting links 82 and 83. The connecting links 82 and 83 have right and left hand threads respectively such that when the sleeve 80 is turned axially, the links 82 and 83 are moved in opposite directions within the sleeve 80.

In order to ensure unison of movement between the two toggle links 74, a cross connected ratchet assembly is mounted upon the sleeves 80 and consists in keyhole shaped member 85 perforated centrally to fit around each sleeve 80. The sleeves 80 are provided with upstanding spline teeth 86, and the keyhole shaped members 85 are recessed in one end of their central perforations to fit around the said teeth 86. Retaining rings 87 secured to the sleeves 80 by set screws 88, serve to hold the said members 85 against the teeth 86. For the purpose of imparting rotation to the sleeves 80, ratchets 90 are mounted in the members 85 directly over the teeth 86. The ratchets 90 are provided with compression springs 92 urging them constantly downward and against the teeth 86, and are further provided with slanting heads 91 adapted to engage the teeth on one side such that rotation of the ratchets 90 in one direction will cause the said ratchets to rise over each tooth compressing the springs 92, but will bear upon the teeth when rotated in the opposite direction. It will be noted that the ratchets 90 may be raised and turned by hand knobs 93 for the purpose of reversing the ratchet action.

The action of the toggle links 74 upon the large shell head 35 is maintained in unison by upstanding handles 94 which are cross connected to one another by means of a cross bar 97. Clevis heads 95 pivotally connect the handles 94 to the said cross bar and thus provide suitable parallel action between the said handles.

The rear bearing assembly 14 consists merely in a bearing case 76 mounted for axial movement in slides 77. Thus it will be seen that the operation of this embodiment of my invention includes adjusting the plug 21 and the shaft 15 axially into or out of the conical shell 16 for the purpose of varying the cutting clearance between the cutter bars 20 and 22. Furthermore by operation of the adjustable toggle links 74, the large shell head 35 may be adjusted away from or closer to the plug head 34, thus giving the stock a larger or smaller path through which to exit from the refiner. In addition, the retarding plug 47 may be advanced or withdrawn to vary the centrifugal motion of the stock after it leaves the chamber 33.

Another embodiment of my invention adapted particularly for high degree refining is shown in Fig. 7 and includes a stator shell 112 encompassed by a water cooling jacket 113 and receiving a conical plug 114 mounted upon a shaft 111 in the manner of conventional jordans. The rear end forms an inlet chamber 119 and is provided with a rear head piece 115, packing 117, and a dirt trap 136, similarly to the embodiment previously described above. The shell 112, however, is lined and the plug 114 is covered by complementary formed sleeves 121 and 123 respectively having opposed lands and grooves machined therein. The said sleeves 121 and 123 are secured to the shell 112 and plug 114 respectively by machine screws and are preferably constructed of dissimilar metals to prevent galling between the said sleeves.

The stock passes forward from the inlet chamber 119 between the sleeves 121 and 123 where it is subjected to their refining action, and then passes into a chamber 120 formed by a plug large head disk 116 and a large shell head 118. The disk 116 is mounted on the large head of the plug 114, and the large shell head is supported by forward extensions 125 of the shell 112. The chamber 120 slopes forward toward the shaft 111 and is provided with a central stock outlet 130 leading to a stock conduit 132.

Upon entering the chamber 120, the stock will be subjected to an intense swirling action and in order to control this a turbulence plug 122 is provided in the large shell head 118. The turbulence plug 118 is similar in operation to the turbulence plug 47 and may either be projected into or withdrawn from the chamber 120 for the purpose of providing resistance to the said swirling action.

The shaft 111 is supported by bearings (not shown) similar to the bearing units 11 and 14, and is moved axially by a conventional worm gear and thrust nut arrangement (not shown). But since it is not expected that the plug 114 will be moved distances comparable to the movement of the plug due to wear when cutter bars are employed, the large shell head 118 is not linked to the shaft front bearing. However, the said large shell head 118 may be adjusted axially by means of a cap 124 tapped to receive threads in the outer periphery of the forward extensions 125 of the shell 112, and further provided with an inwardly extending flange 126. The flange 126 bears upon one side of a cooperating radial flange 127 integral with the large shell head 118, and a back-off lug 128 secured to the cap 124 bears upon the other side of the radial flange 127. Thus the cap 124 may be moved axially by merely turning it, and will carry the large shell head 118 with it by operation of the flanges 126, 127 and the back-off lug 128.

It will be evident that this embodiment of my invention has the effect of subjecting the stock to an extreme hydraulic sheer which in part accounts for the high degree of refinement attained.

While minor variations of the preferred embodiments herein shown will be evident to those skilled in the art, it is not intended to limit the invention to the precise form herein shown, but rather to measure it in terms of the appended claims.

Having thus disclosed preferred embodiments of my invention and described in detail an illus-

trative example thereof, what I claim as new and desire to secure by Letters Patent is:

1. In an apparatus for refining fluent material including a stator shell and a rotor mounted for rotation and axial translation within the shell; the combination of a non-rotatable shell head closing one end of the shell and forming with the end of the rotor a shallow chamber within the shell whereby fluent material within the shallow chamber will be urged radially by the end of the rotor, walls in the shell head forming an outlet passage from said shallow chamber adjacent to the rotor axis, disruption means communicating with said narrow chamber through said shell head including a member movable into or out of said shallow chamber for retarding the centrifugal flow of the said fluent material within the said shallow chamber.

2. In an apparatus for refining fluent material including a stator shell and a rotor mounted for rotation and axial translation within the shell; the combination of a non-rotatable shell head closing one end of the shell and forming with the end of the rotor a shallow chamber within the shell, walls in the shell head forming an outlet passage adjacent to the rotor axis, a turbulence plug mounted in the said large shell head, and means for moving the said turbulence plug into or out of the said shallow chamber whereby the circulatory motion and hence centrifugal counterforce of the said fluent material in the said shallow chamber induced by the said end of the rotor may be regulated to vary the rate of flow of the said material.

3. In a refiner having a stator shell forming a substantially conical matrix and a rotor plug of complementary shape to the matrix mounted on a shaft for rotation axially within the said matrix, wherein fluent material is admitted between the shell and plug at the small end, refined by the cooperative action of the moving plug surface and the stationary shell surface, and urged toward the large end by centrifugal force; means for moving the plug axially relative to the shell, and means providing a uniform outlet path from the refiner for the fluent material despite such plug movement comprising a large shell head spaced from the large end of the plug to form a shallow chamber across the large end of the matrix, walls in the large shell head forming an annular outlet concentric with and adjacent to the shaft, and means for translating the large shell head axially in unison with the plug.

4. In a conical plug type refiner wherein fluent material is treated between the moving surface of a substantially conical rotor plug and the stationary walls of a complementary matrix formed by a stator shell and is urged from the small end to the large end by centrifugal force, means controlling the flow of the fluent material comprising a large shell head spaced from the large end of the plug to form a shallow chamber across the large end of the plug, walls in the large shell head forming an outlet adjacent to the center of the said large shell head, and disruption means communicating with said shallow chamber through said shell head including a member movable into or out of said shallow chamber; whereby the material within the said shallow chamber will be driven circularly by the large end of the rotor plug to create centrifugal force in opposition to the flow of fluent material through the refiner and the said adjustable turbulence means will regulate throughput by

interrupting the said circular movement of the material in the said shallow chamber.

5. A refiner wherein a conical rotor plug is mounted for rotation in a complementary matrix formed by a stator shell, and wherein the surfaces of the plug and matrix lie in spaced relationship and cooperate to refine material passing between them from the apex ends to the large ends of the conical members; having in combination, a large shell head spaced from the large end of the plug to form a narrow chamber across the large end of the refiner, the said large shell head adapted to seal the outer peripheries of the large end of the matrix, and mounted for longitudinal movement along the axis thereof in sealing relation with the said shell, walls in the large shell head forming a central outlet for the said material, means adapted to position the plug along its axis within the said matrix, and a turbulence plug in the large shell head adapted for movement relative to the large shell head whereby smooth centrifugal flow of the said material in the said narrow chamber is disrupted.

6. A jordan-type refiner comprising a shaft, bearings supporting the shaft for rotation and axial movement, a stator shell forming a conical matrix coaxial with the shaft, a conical rotor plug complementary in shape to the matrix mounted on the shaft within the matrix, a large shell head sealing the large end of the stator shell and spaced from the large end of the conical rotor plug to form a narrow chamber, walls forming a stock outlet in the large shell head concentric with and adjacent to the shaft, walls in the large shell head forming a turbulence pocket opening into the narrow chamber, a movable plug forming an end wall for the said turbulence pocket, and means adapted to move the said plug within the said turbulence pocket.

7. In a refiner having a stator shell forming a conical matrix and a conical rotor plug of complementary shape to the matrix mounted on a shaft for rotation axially within the said matrix, wherein stock is admitted between the shell and plug at the apex end, refined by the cooperative action of the moving plug surface and the stationary matrix surface, and urged toward the large end by centrifugal force; a fluted lining for the stator shell, a fluted plug covering, a large shell head spaced from the large end of the plug to form a shallow chamber across the large end of the shell, walls in the large shell head forming a stock outlet concentric with and adjacent to the shaft, and adjustable means communicating with the shallow chamber through the large shell head including a member movable into or out of said shallow chamber to create turbulence in the stock flow within the shallow chamber, whereby stock in the shallow chamber will be subjected to a swirling action by the rotating large end of the plug and the said swirling action will be controlled by the said adjustable turbulence means.

8. In a refiner having a stator shell forming a conical matrix and a conical rotor plug of complementary shape to the matrix mounted on a shaft for rotation axially within the said matrix, wherein stock is admitted between the shell and plug at the apex end, refined by the cooperative action of the moving plug surface and the stationary matrix surface, and urged toward the large end by centrifugal force; spaced cutter bars lining the stator shell, spaced cutter bars secured to the rotor plug, means adapted to move the shaft and plug axially within the shell, walls

integral with the shell forming a cylindrical extension to the said conical matrix, a large shell head spaced from the large end of the plug to form a shallow chamber across the large end of the shell and adapted to slide axially in sealing relation with the said cylindrical extension, walls in the large shell head forming a stock outlet concentric with and adjacent to the shaft, turbulence means communicating with the shallow chamber through the large shell head and including a member movable into or out of said shallow chamber to alter the circulatory path of the stock within the said shallow chamber, and means adapted to move the large shell head axially, whereby stagnation pockets in the stock outlet are eliminated, rate of stock flow may be regulated by the turbulence means and refining conditions in the said shallow chamber may be controlled.

9. In a refiner having a stator shell forming a conical matrix and a conical rotor plug of complementary shape to the matrix mounted on a shaft for rotation axially within the said matrix, wherein stock is admitted between the shell and plug at the apex end, refined by the cooperative

5
10

action of the moving plug surface and the stationary matrix surface, and urged toward the large end by centrifugal force; a shallow conical disk mounted axially upon the large end of the plug, a large shell head spaced in parallel relationship to the said disk to form a shallow chamber across the large end of the matrix, walls in the large shell head forming a stock outlet concentric with and adjacent to the shaft, means adapted to move the large shell head axially, walls in the large shell head forming a turbulence pocket opening into the said shallow chamber, and a movable plug in the said turbulence pocket adapted to control the volume thereof.

CYRUS E. ROBERSON.
